(57) **CLAIM**

The ornamental design for a locking hitch pin, as shown and described.

DESCRIPTION

FIG. 1 is a front perspective view of a locking hitch pin shown in a closed position;

FIG. 2 is a front perspective view of the locking hitch pin of FIG. 1 shown in a partially-opened position;

FIG. 3 is a top plan view of the locking hitch pin of FIG. 1; FIG. 4 is a rear elevation view of the invention illustrated in FIG. 1;

FIG. 5 is a right elevation view of the invention illustrated in FIG. 1;

FIG. 6 is a left elevation view of the invention illustrated in FIG. 1;

FIG. 7 is a bottom plan view of the invention illustrated in FIG. 1;

FIG. 8 is a front elevation view of the invention illustrated in FIG. 3; and,

FIG. 9 is a front elevation view of the locking hitch pin of FIG. 1 depicted in a fully-opened position.
